PROCESS FOR BENDING BARS AND THE LIKE.

Application filed September 28, 1926. Serial No. 138,139.

This invention relates to processes for bending metal members, such as bars, rods, strips, or the like.

The objects of this invention are to provide a process for bending metal members or parts of metal members edgewise in such a manner as to avoid the distortion of the members out of their respective planes; also to provide a process whereby angle bars and the like may be bent in such a manner that a flange thereof extends inwardly toward the center of curvature, and without changing the true cross section of the bar at any portion thereof; also to improve processes of this kind in other respects hereinafter specified.

In the accompanying drawings,

Fig. 1 shows respectively a face view and an edge view and a section of a flat bar or strip of metal which is to be bent edgewise.

Fig. 2 shows the face view of the bar or strip of metal after the same has been bent edgewise, a cross section thereof being shown below the face view thereof.

Fig. 3 shows an angle bar before the same has been bent, and a cross sectional view thereof.

Fig. 4 shows an angle bar after the same has been passed through the first operation, and a cross section thereof.

Fig. 5 shows the angle bar after the same has been bent into its final shape, and a cross section thereof.

Fig. 6 is a fragmentary, side elevation of a metal bending machine which may be used for effecting the final bending operation on the bar.

Fig. 7 is a front elevation thereof, showing the same used in the ordinary manner for bending a bar.

Fig. 8 is a front elevation of a bending machine similar to that shown in Fig. 7 and showing my improved attachment in place thereon, said attachment being used for compressing an edge of the work to effect an edgewise bending thereof.

Fig. 9 is a side elevation, on an enlarged scale, of said attachment.

Fig. 10 is a front elevation of the attachment.

Fig. 11 is a fragmentary, top plan view of a bending machine showing a bar passing through the same and being bent by the elongation of an edge of a flange of the bar.

It is well known that any substantially flat metal member such as a strip of metal, or a flat portion of a member, such as a flange of a beam or bar, offers great resistance to bending in planes parallel to its flat surface, and it is also very difficult to bend a substantially flat member in this manner for the reason that this member tends to become deformed or to buckle out of its own plane. In the bending of angle bars, it has been found that if the bar is to be bent in such a manner that one flange extends cylindrically about the axis of curvature and the other flange or flanges extend outwardly therefrom, no difficulty is encountered since the outer edge of the outwardly extending flange or flanges can readily be elongated to permit the desired curvature to be attained, and the flanges after being bent will retain the correct angular relationship to each other. If, however, the bar or beam is to be bent in one operation in such a manner that the flange or flanges lying in planes radial to the axis of curvature, extend inwardly or toward the axis of curvature, a deformation of the cross sectional shape of the bar or beam results, so that the circumferential flange does not extend at right angles to the radial flange, but forms an acute angle therewith, which is objectionable for many purposes.

I have found that angle bars and the like can be bent with one flange thereof extending radially toward the axis of curvature from the other flange by subjecting the bar to two different bending actions, to wit, in the first place, bending or curving a bar at right angles to its final bend or curvature, and then bending a bar which has been so curved into its final form. The first bending operation must take place in such a manner that the flange which ultimately becomes the cylindrical or circumferential flange of the final bar, is first bent in such a manner that this flange becomes the outwardly extending flange of the angle bar extending outwardly from the axis of curvature and from the other flange. The bar which is thus curved is then passed through a bending machine or subjected to a bending action in any other suitable or desired manner so that the outwardly curved flange becomes the circumferential or cylindrical flange of the ultimate bar, and so that the other flange is bent in a plane radial to the 110

axis of curvature and extends toward the axis of curvature from the other flange.

Referring to the drawings, Fig. 3 shows an angle bar having flanges A and B, and which angle bar is to be bent or curved in such a manner that the flange A extends inwardly or toward the axis of curvature, while the flange B is to become the cylindrically curved or circumferential flange. In accordance with my process the bar is first subjected to a bending or curving operation so that the same assumes a shape approximately as illustrated in Fig. 4 in which the flange A extends substantially cylindrically around the axis of curvature while the flange B extends outwardly therefrom. This curved bar is then subjected to a second bending operation, which may be done in the usual bending machine, for example, as illustrated in Figs. 6 and 7, so that the flange B passes between the rolls in contact with the opposite faces of the bending rolls and is bent to form the cylindrical flange of the finally bent bar. By giving the bar during its first bending operation the correct curvature, corresponding to the ultimate curvature desired, it has been found that when this curved bar is bent into its final shape, the flange A is bent in such a manner that it will lie entirely in a single plane, in other words that the cylindrical curvature of the flange A, as shown in Fig. 4, is entirely eliminated by the final bending of the bar. The bending of the flange A from the curvature shown in Fig. 4 into a single plane by merely applying pressure of the bending rolls to the flange B, as shown in Fig. 7, is due to the fact that the bending of a bar of the form shown in Fig. 4 to that shown in Fig. 5 can only be effected by elongating the adjoining edges of the flanges A and B. During the bending of the flange A from the shape shown in Fig. 4 to that shown in Fig. 5, the edge of this flange nearest the center of curvature cannot be compressed or shortened to any appreciable extent, and consequently the metal of the edge of the flange further from the center of curvature must be stretched or elongated, together with adjacent parts of the flange B. However the edge *b* of the flange B is not stretched during this bending of the bar. Consequently the stretching or elongation of metal of the bar at the juncture of the flanges, together with the fact that the metal at the edge portion *b* is not elongated, causes the angle bar to be bent in such a manner that the flange A is again bent into a single plane. In order to produce a correctly curved bar as shown in Fig. 5, it is necessary to produce in the first operation the proper curvature of the bar or elongation of the edge *b* thereof, to correspond to the final curvature desired. As the result of these two bending operations the finally bent bar as shown in Fig. 5 will be

of correct cross sectional shape, with the two flanges thereof at substantially right angles to each other.

The bending or curving of the bars may be carried out by any suitable or desired instrumentalities. In Figs. 6 and 7 is shown a bending machine of a construction frequently used in connection with the bending of bars, this machine including a housing 15 on which three rolls 16, 17 and 18 are journaled on shafts extending outwardly beyond the end of the housing, and these rolls may be adjustable relatively to each other in any suitable or desired manner, the upper roll 16 being adjustable toward the two lower rolls 17 and 18 in the construction shown, a hand wheel 19 and suitable mechanism (not shown) being preferably employed for this purpose, and the rolls 16, 17 and 18 are preferably made in two parts 85 spaced apart to provide annular slots 20 between the two parts of the rolls into which a flange of the bar or beam which is being bent may extend. These rolls are, of course, driven by any suitable source of power so that all rolls rotate at the same speed, and when a bar is passed between them, for example from the right to the left as shown in Fig. 7, the bar is bent as illustrated in this figure.

In connection with the process described I have found that where angles with unequal legs as those shown in Figs. 3, 4 and 5 are to be bent so that the widest flange B extends outwardly from the center of curvature, difficulties are frequently encountered. For cases of this kind I have devised an improved process of and mechanism for bending which consists of subjecting the outer portion or edge of a flange or of a flat plate or strip to an elongating action which may be effected by cold rolling under pressure. For example if a strip of material such as shown at C in Fig. 1 or a relatively wide flange as the flange B in Fig. 3 is to be bent 110 edgewise, in other words in its own plane, considerable difficulty is encountered if this is done in ordinary bending machines since it is almost impossible to bend a flat bar or flange or part of a bar edgewise without buckling the opposite side faces of such a bar or strip out of their planes. I have found, however, that if a portion of a side of a bar, for example a side *c* shown in Figs. 1 and 2 is subjected to rolling under pressure, which may be done while the bar is cold, an elongation of the side *c* results which causes a curving of the bar from the form shown in Fig. 1 to the form shown in Fig. 2 with a very small reduction in the thickness of the 125 bar. This rolling operation may also be applied to angle bars for bending the same. Consequently in the case of the angle bar shown in Figs. 3 and 4 the preliminary curving of the angle bar is preferably effected 130

by applying a rolling pressure to the side *b* of the flange B of the angle so that a rolling under pressure of this side of the flange results and a corresponding elongation thereof. This produces the desired curvature of the bar. Other means for producing this curvature of the bar may, however, be used without departing from this invention.

A bending machine such as shown in Figs. 6 and 7 may be quickly adapted for bending a bar or strip of material by rolling out an edge portion thereof. For this purpose the following construction may be employed. As shown in Fig. 8, three small rolls are provided, to wit, rolls 21, 22, and 23, the last two of which are pivoted in a suitable bearing or guide housing 24 provided with a downwardly extending guide portion 25 which extends between the two rolls 17 and 18. The two rolls 22 and 23 bear respectively on the rolls 17 and 18 and receive rotary motion therefrom, which rotary motion is transmitted to the roll 21 which rests loosely upon the two rolls 22 and 23 and the upper face of this roll 21 extends into proximity to the lower face of the roll 16 of the bending machine. By adjusting the rolls of the bending machine relatively to the rolls of the rolling element, the distance between the upper surface of the roll 21 and the lower surface of the roll 16 can be adjusted accurately, and if this distance is adjusted to be slightly less than the thickness of the part to be rolled, a rolling out or elongation of the part will result. Fig. 10 shows a bar passing through the machine to be acted upon by the rolls 16 and 21 so that the free edge portion *b* of the flange B is subjected to a rolling action, which results in an elongation of this portion of the flange B.

In the construction described the rolling element consisting of the rolls 21, 22 and 23, and the housing can be readily inserted between the rolls 16, 17 and 18 in such a manner that the two rolls 22 and 23 bear on and receive rotary motion from the rolls 17 and 18 respectively. This in turn causes a rotation of the roll 21 at the same peripheral speed as the roll 16, so that the rolling action of a bar, plate or strip can be readily effected. The rolling device shown is so made that the pressure is transmitted from the roll 21 to the rolls 22 and 23 and from the rolls 22 and 23 to the rolls 17 and 18, so that very little or no pressure is exerted on the bearings of the rolls 22 and 23 in the housing 24, the pressures being transmitted only through the rolls themselves. The bearings of these rolls 22 and 23, therefore, only serve to hold the rolls in correct relation to each other and to the bending rolls 16, 17 and 18. The downwardly extending guide portion 25 extends between the rolls 17 and 18 and serves to hold the rolling attachment in

correct relation to the rolls so that no securing of the attachment is necessary, but merely a placing or positioning of the rolling attachment between the rolls. In case there is any tendency of the device to tilt, the guide portion 25 will engage one or the other of the rolls 17 or 18 and thus limit the tilting movement of the rolling device. If desired a bar may be passed between the rolls 16 and 21 a number of times until the desired curvature is obtained, the rolls being gradually brought closer together so that a gradual rolling out or elongation is effected of the part of the work which is acted upon by the rolls. When it is then desired to give the bar the second bending operation, the rolling attachment can be quickly removed from its position between the rolls 17 and 18 and by lowering the roll 16 into its operative position, the bar may be passed through the bending machine in the usual manner to receive the second bending thereof.

The bending of a bar, rod or part by means of pressure rolling has the important advantage that there is no tendency of the part which is being bent to buckle or bend out of the original plane of its flat faces. This pressure rolling also has the advantage that the work can be uniformly curved from end to end thereof, while with bending machines as heretofore used, a certain length of bar at each end of the work could not be bent or curved.

I claim as my invention:

1. The process of bending angle shaped bars in such a manner that one of the flanges extends toward the center of curvature while the other flange extends cylindrically about the center of curvature, consisting of first bending said bar in a plane parallel to

said other flange so that the free edge thereof is convexly curved, and then bending said bar in a direction substantially at right angles to the plane of said other flange to cause said first mentioned flange to extend toward the center of curvature and into a plane.

2. The process of bending angle shaped bars into a form in which one flange thereof extends cylindrically about the center of curvature and the other flange extends toward the center of curvature from said first mentioned flange, consisting of rolling under pressure the outer edge portion of said first mentioned flange to elongate the same and to curve said bar, and then bending said first mentioned flange in a direction transverse to the plane thereof to cause said other flange to extend inwardly from said first mentioned flange toward the center of curvature.

3. The process of bending an angle bar with one flange thereof extending inwardly with reference to the other flange, consisting of subjecting the outer edge portion of said other

flange to a rolling action to elongate the outer edge portion of said other flange and then bending said bar in a direction substantially at right angles to the plane of said other flange.

4. The process of bending angle shaped bars, consisting of bending the bar so that one flange thereof extends outwardly from the second flange and the second flange extends substantially cylindrically with reference to the axis of curvature, and then bending said bar in a direction perpendicular to said first mentioned flange to cause said second flange to extend from said first mentioned

15 flange toward the axis of curvature.

5. The process of bending angle shaped bars with one flange thereof extending inwardly toward the axis of curvature with reference to the other flange, consisting of 20 first elongating the outer edge of said other flange and then bending said bar in a direction perpendicular to the flat faces of said other flange and producing a corresponding elongation of the inner edge of said other flange, whereby the edges of said other flange 25 are caused to lie each substantially in a plane.

6. The process of bending angle shaped bars with one flange thereof extending inwardly toward the axis of curvature with reference to the other flange, consisting of 30 first curving said bar to elongate the outer edge of said other flange, and then bending said bar in a direction perpendicular to said other flange and to cause said first flange to extend from said other flange toward the axis of curvature, to reduce the curvature produced by the first bending 35 operation.

40 7. The process of bending angle shaped bars with one flange thereof extending inwardly toward the axis of curvature with reference to the other flange, consisting of first elongating the outer edge of said other flange and then bending said bar in a direction 45 perpendicular to the flat faces of said other flange and producing a corresponding elongation of the inner edge of said other flange, due to the bending of said 50 first mentioned flange in a direction cross-wise thereof.

8. The process of bending angle shaped bars into a form in which one flange thereof extends cylindrically about the center of curvature and the other flange extends toward the center of curvature from said first mentioned flange, consisting of elongating the outer edge portion of said first mentioned flange, and then bending said first mentioned flange in a direction perpendicular 60 to the flat faces thereof to cause said other flange to be bent edgewise and thereby produce a corresponding elongation of the other edge portion of said first mentioned flange.

65 9. The process of bending angle shaped bars into a form in which one flange thereof extends cylindrically about the center of curvature and the other flange extends toward the center of curvature from said first 70 mentioned flange, consisting of elongating the outer edge portion of said first mentioned flange by curving said bar to an extent depending upon the ultimate curvature desired, and then bending said first mentioned 75 flange in a direction perpendicular to the flat faces thereof to cause said other flange to be bent edgewise and thereby produce a corresponding elongation of the other edge portion of said first mentioned flange to 80 cause said other flange to be bent into a plane.

10. The process of bending a bar having a plurality of flanges into a form in which one of said flanges extends cylindrically about the axis of curvature and the other flange extends inwardly from said cylindrical flange toward the axis of curvature, consisting of first bending said bar in a direction parallel to said first mentioned 90 flange and producing an elongation of the outer edge of said first mentioned flange, and then bending said bar in a direction substantially at right angles to said first mentioned flange to cause said other flange to 95 extend toward the center of curvature, to produce an elongation of the edge of said first mentioned flange adjoining said other flange corresponding to the elongation of the outer edge of said first mentioned flange.

ARTHUR T. YATES.
